UNITED STATES PATENT OFFICE

2,369,592

METHOD OF TREATING BOBBINS

Davis Marinsky and Louis H. Morin, Bronx, N. Y.

Application April 3, 1943, Serial No. 481,776

4 Claims. (CL 112—251)

This invention relates to what is commonly referred to as bobbins used with the shuttles of sewing machines or devices of this type and kind supporting threads, lines, cord and the like. More particularly, the invention relates to the method of treating wound devices of this kind so as to establish between contacting strands of the device an adhesion sufficient to maintain the strands against accidental displacement or undesirable unwinding while at the same time facilitating forceable removal of the strands, and further to adding lubricating properties to the strand.

The novel features of the invention will be best understood from the following description when taken together with the accompanying drawing, in which certain embodiments of the invention are disclosed, and in which the separate parts are designated by suitable reference characters in each of the views, and in which:

Fig. 1 is a diagrammatic sectional view indicating in dotted lines the submersion of a plurality of bobbins, and in full lines the step of rotating the bobbin basket or container in the removal of surplus coating material therefrom; and

Fig. 2 is a diagrammatic sectional view showing the step of dispensing the coated bobbins onto a receiver.

In the construction of bobbins, spools and other wound strand products of the type and kind under consideration, particularly as taught in our prior application 423,934 as well as in our Patents 2,200,720 and 2,200,721, it has been the practice to mount the bobbins or other devices on spindles, prior to partially or wholly submerging the same in a coating material, and then to rotate these spindles to remove the surplus coating or saturating material. This method of procedure has been objectionable primarily from the standpoint of the loss of time in mounting the bobbins or other devices on the spindles.

To overcome the objectionable features to these known methods, we have conceived a method which consists in simply mounting a plurality of bobbins or other devices in what might be termed a basket of open work material. Then we submerge the basket with the bobbins therein in a coating or penetrating solution, allowing the same to be submerged for a predetermined period of time. Then the basket is raised from the solution and rotated at high speed, while still contained within the vat or container for said solution, to remove surplus coating or saturating material from the bobbin by the action of centrif-

ugal force. Then we automatically dump, dispense or otherwise remove the processed bobbins from the basket, after which the basket is again filled and the above process repeated. With this method, large quantities of bobbins or other devices can be speedily coated or otherwise treated with wax or other materials.

In the accompanying drawing is diagrammatically illustrated one procedure in carrying out the method, in which 10 represents a vat or tank in which is placed the coating or saturating solution 11 to be employed. For purposes of this description the use of wax or paraffin will be described. At 12 is shown a suitable heater for maintaining the wax 11 at a desired temperature. It will appear that the upper edge of the vat 10 has an inturned flange portion 13 to prevent displacement of the wax, particularly in the centrifugal discharge, later described.

10 In the accompanying drawing, we will not deal with apparatus phases, insofar as the disclosure is concerned, more than to diagrammatically portray the general steps of the method. It will be understood, however, that apparatus such as generally indicated in application 423,934 can be employed, modified to the necessary extent in dealing with the different structure disclosed in the present case. At 14 is shown a spindle which carries at the lower end thereof a basket or other 15 open work container 15. This basket may comprise perforated material or may be in the form of a wire mesh construction.

16 The basket 15 has a circular peripheral wall 16 with openings 17 therein, and this wall includes an inturned top flange portion 18, which leaves a large admission opening 19 in the top of the basket. Transversing the lower edge portion of the wall 16 is a substantially triangular bar 20, to the central portion of which the spindle 14 is riveted, as seen at 21. The bar 20 carries at opposite sides thereof pintle bearings 22 in which are mounted pintle pins 23, which also pass through bearings 24 on hinged bottom plates 25, forming the bottoms of the basket.

10 25 The bottom plates 25 which might also be termed "drop doors" have openings 26 to allow the wax to drain freely therethrough in raising the basket out of the body of wax into the full line position indicated in Fig. 1. The bottom plates or doors 25 include centrally of the outer edges thereof clip ends 27 adapted to engage projections 28 on the wall 16 to retain the bottoms in closed position. At this time, it will be understood that any type of securing means can be employed, and in some instances positive me-

chanical means may be employed to operate the doors 25 to move the same into open and closed position.

In Fig. 2 of the drawing the basket is shown in raised position above the vat or container 10, with the doors 25 in open position, and with a pan or other receptacle 29 arranged beneath the raised basket, so that the bobbins 30 may be dumped into the pan or receptacle 29. After this operation the basket may be raised still further to remove the pan 29, the doors 25 moved into closed position, and an additional supply of bobbins inserted in the basket through the opening 19.

The steps of the method of coating and saturating bobbins will be understood when taken in connection with the diagrammatic illustrations in the drawing and the following statement. Starting with the filling of the basket 15 with the required number of bobbins, the basket with the bobbins therein is then lowered into the dotted line position shown in Fig. 1, and retained in this position for a predetermined period of time which may be automatically controlled in any desired manner. In this connection it will be understood that the time period will vary with products of different types and kinds and with different coating and saturating materials employed.

When the time for coating or saturation has expired, the basket 15 is raised into the full line position shown in Fig. 1, after which the shaft or spindle 14 is rotated at high speed and centrifugal force will operate to discharge all surplus material from the bobbins. Here again, this step in the operation or method of procedure will be controlled to insure removal of all free or excess coating material.

Having completed the spinning or centrifugal discharge of surplus wax, the basket is now raised sufficiently to permit insertion of the pan 29 there beneath, after which the two doors 25 will be dropped to discharge the bobbins into the pan 29, after which the basket is raised to provide free removal of the pan, and the doors 25 are then closed and the above operation repeated.

As taught in the application hereinbefore identified, the dispensing and re-filling of the basket may take place at a station spaced with respect to the applicator station where the vat 10 is located, in order to speed up the production and enable the operator to saturate one group of bobbins while the pre-saturated or coated group are discharged from the basket and the basket re-filled.

The resulting bobbin prepared in accordance with the method above described will have the contacting portions of the threads united by the coating and saturating wax employed, sufficiently to support the threads against accidental displacement and unwinding, thus eliminating the necessity of using conventional spools having side wall portions for holding the strands against displacement. The uniting of crossed strands is not sufficient, however, to prevent normal withdrawal of the thread or strand in the use of the bobbins.

It will be understood that the size, shape and construction of the basket will depend entirely upon the type and kind of wound thread or strand product to be processed according to the invention. Where conventional small bobbins are being processed, large quantities of these bobbins can be arranged in a comparatively small basket. In the high speed rotation of the basket for removal of surplus coating material, the bob-

bins will be maintained adjacent the peripheral wall 16 of the basket and will also be shifted to various positions from horizontal to vertical. The bobbins arranged thus will dump readily onto the receptacle or pan 29 when the doors 25 are lowered. The conical top of the bar 20 will also aid in this operation.

While our process is adaptable for use in the treatment of strand bodies of any kind or class, 10 regardless of how the strands are wound thereon, where such bodies include the cross wound strands, these strands establish what might be considered points of contact, and these will adhere in maintaining the accidental unwinding 15 of the strands while at the same time permitting unwinding of the strands in the use of the bobbin.

It will be understood that in the process of 20 treating the bobbins or other bodies with wax or other material which is heated, definite control will be provided to maintain the desired temperature during operating conditions. At the same time a definite control is provided for the 25 time of submersion of the bobbins in the body of wax, as will also be true of the time period of rotation of the basket in dispensing of surplus wax by action of centrifugal force. These time controls are important, particularly from the 30 standpoint of automatic high speed of production of bobbins and other bodies, according to the invention, and particularly from the standpoint of producing all automatic operations as much as possible. Furthermore, by definitely controlling the time period of the different steps 35 of the method, uniformity can be established and maintained in the resulting products to satisfy predetermined conditions. Where different conditions are required to suit different products or uses of the products, the control time periods may be varied in all or some of the steps of the method.

Having fully described our invention, what we claim as new and desire to secure by Letters Patent is:

1. A method of treating bobbin bodies including a strand of thread cross wound on a core for retaining the thread against inadvertent unwinding and for retaining the mass of wound thread on the core in the absence of retaining discs, 40 which comprises the steps of arranging groups of bodies freely in an open work supporting member, submerging said member with said bodies therein in a fluid, maintaining the bodies in the fluid for a predetermined period of time to saturate all of the windings of the strand on each of said bodies, then removing the member and said bodies from the fluid and rotating said member at high speed with a resultant movement of the bodies relatively to and toward the peripheral wall of the work supporting member to dispense 45 surplus fluid from the strand windings of said bodies and all fluid intervening the strand windings through said member by subjecting said bodies as a whole to the action of centrifugal force, then removing all of the bodies collectively and simultaneously from said member, and then drying said bodies to harden the fluid applied to the strands thereof, producing in the resulting wound bodies slight adhesion between contacting portions only of adjacent strand windings preventing accidental displacement and inadvertent unwinding of the windings from said bodies.

2. A method of treating bobbin bodies including a strand of thread cross wound on a core for retaining the thread against inadvertent unwind-

ing and for retaining the mass of wound thread on the core in the absence of retaining discs, which comprises the steps of mounting a plurality of said bodies freely in an open work basket supported on a rotatable spindle, submerging the basket with the bodies therein in wax heated at a predetermined temperature, maintaining the bodies in the heated wax for a predetermined period of time to coat all of the windings of the strand on said bodies, then removing the basket and said bodies from the heated wax, then rotating said spindle and basket at high speed with a resultant movement of the bodies relatively to and toward the peripheral wall of the work supporting basket to discharge surplus wax from the windings of all of said bodies and all wax intervening the windings by subjecting said bodies as a whole to the action of centrifugal force, controlling the time of rotation of the spindle to insure removal of the wax, then removing all of the bodies collectively and simultaneously from said basket, and then drying said bodies to harden the wax applied to the strands thereof, producing in the resulting wound bodies slight adhesion between contacting portions only of adjacent strand windings preventing accidental displacement and inadvertent unwinding of the windings from said bodies.

3. A method of treating bobbin bodies including a strand of thread cross wound on a core for retaining the thread against inadvertent unwinding and for retaining the mass of wound thread on the core in the absence of retaining discs, which comprises heating a large quantity of wax to a predetermined and controlled temperature, submerging a plurality of bobbins freely arranged in an open work container in said heated wax, controlling the time period of submersion of the bobbins in the wax to saturate all of the windings of the thread on each of said bobbins, then removing the bobbins and said container from the wax and rotating the container at high speed for a controlled period of time with a resultant movement of the bodies relatively to and toward

the peripheral wall of the container to remove surplus wax from the bobbins by subjecting said bodies as a whole to the action of centrifugal force, then removing all of the bobbins simultaneously from said container, and then drying the bobbins to set the wax on the threads thereof so as to establish slight adhesion between contacting portions only of adjacent thread windings on each bobbin to retain the thread against accidental displacement and inadvertent unwinding.

4. A method of treating bobbin bodies including a strand of thread cross wound on a core for retaining the thread against inadvertent unwinding and for retaining the mass of wound thread on the core in the absence of retaining discs, which comprises establishing two stations, namely a loading and unloading station and a submerging station, depositing a predetermined number of strand bodies freely in a basket type carrier at the loading station, then moving the carrier to the submerging station and submerging all of the bodies in the carrier in heated wax at said submerging station, maintaining said bodies submerged in the wax sufficiently to saturate all of the windings of said bodies, then moving the carrier to remove the bodies from the heated wax while maintaining said bodies at said station and above the heated wax, then rotating the carrier at high speed with a resultant movement of the bodies relatively to and toward the peripheral wall of the carrier to remove all surplus wax from said bodies by subjecting said bodies as a whole to the action of centrifugal force, then returning the carrier to the first named station and unloading the treated bodies simultaneously from the basket of said carrier, and then drying said bodies to harden the wax and producing in the resulting bodies slight adhesion between contacting portions only of the windings on said bodies preventing accidental displacement and inadvertent unwinding of the strands from said bodies.
